United States Patent Office

Des. 179,973
Patented Apr. 2, 1957

179,973

SERVING TRAY

Thomas P. Housley, Miami, Fla.

Application April 30, 1956, Serial No. 41,255

Term of patent 7 years

(Cl. D44—10)

Fig. 1

Fig. 2

Fig. 5

Fig. 4

I claim:

The ornamental design for a serving tray, substantially as shown.
